Patented Oct. 27, 1925.

UNITED STATES PATENT OFFICE.

FREDRICH OLSEN, OF DOVER, NEW JERSEY.

SHELL FILLER.

Application filed January 9, 1923. Serial No. 611,609.

(GRANTED UNDER THE ACT OF MARCH 3, 1883; 22 STAT. L. 625.)

To all whom it may concern:

Be it known that I, FREDRICH OLSEN, a citizen of the United States, and a resident of Picatinny Arsenal, Dover, county of Morris, and State of New Jersey, have invented an Improvement in Shell Fillers, of which the following is a specification.

The invention described herein may be used by the Government, or any of its officers or employees in prosecution of work for the Government, or by any other person in the United States, without payment to me of any royalty thereon, in accordance with the act of March 3, 1883.

The subject of this invention is an explosive device, for example, a projectile.

The main object of the invention is the provision of an explosive device suitable for warfare, loaded with a stable explosive possessing requisite bursting force for use in high explosive shells.

With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

In the accompanying drawing I have illustrated a high explosive shell containing a bursting charge in accordance with my invention.

Referring to the drawing, I provide a container, herein shown as a shell 1 having a cavity therein in which is placed guanidine picrate 2 and provided with the usual type fuse 3 for initiating the explosion of the guanidine picrate.

I have found after considerable experimentation that guanidine picrate may be loaded in shells or other containers and especially armor piercing shells and produce an explosive device possessing many desired characteristics, such as, safety in handling, insensitiveness to shock, stability, etc.

The guanidine picrate may be loaded into the shell directly or it may be cast or extruded with a suitable binder, such as paraffin or T. N. T. or other material, either inert or explosive, possessing a suitable melting point or the liquified substance carrying guanidine picrate may be poured directly into the shell. While an explosive device of excellent quality is produced by loading a container in any of the ways heretofore described I have found that desirable results are also obtained by compressing the guanidine picrate to a density of not less than 1.50.

I claim:

1. A filler for projectiles embodying guanidine picrate compressed to a density of not less than 1.50. 65

2. A filler for projectiles embodying a charge compressed to a density of not less than 1.50, said charge comprising guanidine picrate and a substance possessing a low melting point, said substance serving when melted as a vehicle for carrying the picrate in filling a shell and when solidified as a binder for the picrate.

3. A filler for projectiles embodying a charge compressed to a density of not less than 1.50, said charge comprising guanidine picrate, and a substance possessing a low melting point whereby the shell may be filled by casting or extrusion. 75

FREDRICH OLSEN.
